UNITED STATES PATENT OFFICE

THOMAS M. PUTNAM, OF CEDAR GROVE, WISCONSIN

DESIGN FOR AN ELECTRIC STOVE

Application filed February 21, 1930. Serial No. 34,619. Term of patent 14 years.

To all whom it may concern:

Be it known that I, THOMAS M. PUTNAM, a citizen of the United States, residing at Cedar Grove, in the county of Sheboygan and State of Wisconsin, have invented a new, original, and ornamental Design for Electric Stoves, of which the following is a specification, reference being had to the accompanying drawing, forming a part thereof, and in which—

Figure 1 is a view in front elevation of an electric stove showing my new design;

Figure 2 is a view in side elevation of the stove shown in Figure 1; and

Figure 3 is a view thereof in top plan.

I claim:

The ornamental design for an electric stove as shown.

THOMAS M. PUTNAM.
